[57] CLAIM

The ornamental design for an air purifier with illuminating outer ring, as shown.

DESCRIPTION

FIG. 1 is a top view of an air purifier according to the present invention;

FIG. 2 is a front view of the air purifier according to the present invention as shown in FIG. 1;

FIG. 3 is a bottom view of the air purifier according to the present invention as shown in FIG. 1;

FIG. 4 is a rear view of the air purifier according to the present invention as shown in FIG. 1;

FIG. 5 is a right side view of the air purifier according to the present invention as shown in FIG. 1;

FIG. 6 is a left side view of the air purifier according to the present invention as shown in FIG. 1; and,

FIG. 7 is a perspective view of the air purifier according to the present invention as shown in FIG. 1.
